DESIGN FOR A COMBINATION JAR LID LIFTER AND BOTTLE CAP REMOVER

Earl J. Welch, Lorain, Ohio

Application April 1, 1944, Serial No. 113,115

Term of patent 14 years

(Cl. D44—29)

To all whom it may concern:

Be it known that I, Earl J. Welch, a citizen of the United States, residing at Lorain, in the county of Lorain and State of Ohio, have invented a new, original, and ornamental Design for a Combination Jar Lid Lifter and Bottle Cap Remover, of which the following is a specification, reference being had to the accompanying drawing, forming a part thereof.

Figure 1 is a side elevational view of a combination jar lid lifter and bottle cap remover, showing my new design;

Figure 2 is an edge elevational view thereof; and

Figure 3 is a side elevational view showing the other side of the combination jar lid lifter and bottle cap remover shown in Figure 1.

I claim:

The ornamental design for a combination jar lid lifter and bottle cap remover, as shown.

EARL J. WELCH.
